US0D1035047S

(12) **United States Design Patent** (10) **Patent No.:** **US D1,035,047 S**
(45) **Date of Patent:** **** Jul. 9, 2024**

(54) **BALUSTER**

(71) Applicant: **House of Forgings, LLC**, Houston, TX (US)

(72) Inventor: **Justin James Palazzo**, Houston, TX (US)

(73) Assignee: **House of Forgings, LLC**, Houston, TX (US)

(**) Term: **15 Years**

(21) Appl. No.: **29/864,665**

(22) Filed: **Jun. 10, 2022**

(51) **LOC (14) Cl.** **25-01**

(52) **U.S. Cl.** **USPC** **D25/126**
